US00D958816S

(12) **United States Design Patent** (10) **Patent No.:** **US D958,816 S**
Sit et al. (45) **Date of Patent:** **** Jul. 26, 2022**

(54) **DISPLAY SCREEN OR PORTION THEREOF WITH GRAPHICAL USER INTERFACE**

(71) Applicant: **Smiths Medical ASD, Inc.**, Plymouth, MN (US)

(72) Inventors: **Richard Sit**, Chanhassen, MN (US); **Ross Gencheff**, Madison, WI (US); **Michael Kersch**, St. Michael, MN (US); **Valerie Schiebel**, Otsego, MN (US); **Alejandro Ojeda Saint-Martin**, Bloomington, MN (US); **Shelby Erickson**, Woodbury, MN (US); **Jonathan Sollie**, Minneapolis, MN (US)

(73) Assignee: **Smiths Medical ASD, Inc.**, Plymouth, MN (US)

(**) Term: **15 Years**

(21) Appl. No.: **29/652,719**

(22) Filed: **Oct. 29, 2020**

(51) LOC (13) Cl. **14-04**

(52) U.S. Cl.

(57) **CLAIM**

We claim the ornamental design for a display screen or portion thereof with graphical user interface, as shown and described.

DESCRIPTION

FIG. 1 is a front view of a display screen or portion thereof with graphical user interface; and,

FIG. 2 is a front view of FIG. 1 depicted on a device. The broken lines in the drawings illustrate portions of the display screen or portion thereof with graphical user interface that form no part of the claimed design.

1 Claim, 2 Drawing Sheets
